MULLING APPARATUS

Elmer O. Beardsley and Walter E. Naylor, Chicago, Ill., assignors to The Beardsley & Piper Company, Chicago, Ill., a corporation of Illinois

Application September 4, 1937, Serial No. 162,452

23 Claims. (Cl. 83—45)

The present invention relates generally to apparatus for mulling or mixing granular material. More particularly the invention relates to that type of mulling apparatus which is designed primarily for use in a foundry or like establishment in connection with the mulling or mixing of moulding sand and comprises (1) a frame structure; (2) an open top sand retaining receptacle which is mounted on and supported by the frame structure and embodies a substantially flat circular bottom and an outwardly bulged side wall which is of substantially semicircular cross-section and extends outwardly and upwardly and then inwardly from the outer margin of the bottom; (3) a plurality of cross-head supported balls which are arranged within the receptacle to travel in a circular course around the outwardly bulged side wall and are adapted during such travel to spin and effect the desired mulling or mixing of the sand between them and the side wall; (4) sets of scrapers and plow type deflectors which are supported by the cross-head for conjoint travel with the balls and serve respectively during operation of the apparatus to scrape the mulled sand from the side wall of the receptacle and to deflect the scraped sand back against the side wall into the path of the balls; and (5) an electric motor which is mounted on the frame structure and is connected through the medium of speed reducing gearing and the cross-head to drive or propel the balls, scrapers and deflectors.

One object of the invention is to provide a mulling apparatus of this type which is generally an improvement upon and is more practical and efficient than previously designed mulling apparatus of the same general character.

Another object of the invention is to provide a mulling apparatus of the type under consideration in which the outwardly bulged side wall of the receptacle is in the form of an annular series of complementary sections which are removably secured together so that one or more may be disconnected from the remainder in order to provide access to the balls, scrapers and deflectors for repair or removal purposes.

Another object of the invention is to provide a sand mulling apparatus of the last mentioned character in which one of the aforementioned complementary sections embodies an outwardly swinging discharge door for the mulled sand, and the outwardly bulged side wall is releasably clamped to the bottom of the receptacle so that it may be turned or adjusted bodily in order to bring the discharge door into any desired angular

position with respect to the supporting structure.

Another object of the invention is to provide a mulling apparatus of the type and character under consideration in which the mulling balls are fixed to the lower ends of substantially vertically extending shafts which have the upper ends thereof rotatably mounted in fixed bearings on the cross-head so that the balls are permitted to spin during travel around the outwardly bulged side wall but are held in fixed spaced relation with said side wall and thus effect squeezing of the sand between them and the side wall during operation of the apparatus.

A further object of the invention is to provide a mulling apparatus of the aforementioned type in which the scrapers and plow type deflectors are so connected to the cross-head that in the event they encounter scrap or other foreign articles in the sand during operation of the apparatus they are permitted to swing inwards out of their operative position and thus release the scrap and prevent it from producing a wedging action and either damaging the outwardly bulged side wall or the scrapers and plow type deflectors.

Other objects of the invention and the various advantages and characteristics of the present mulling apparatus will be apparent from a consideration of the following detailed description.

The invention consists in the several novel features which are hereinafter set forth and are more particularly defined by claims at the conclusion hereof.

In the drawings which accompany and form a part of this specification or disclosure and in which like numerals of reference denote corresponding parts throughout the several views:

Figure 1 is a vertical longitudinal sectional view of a sand mulling apparatus embodying the invention;

Figure 2 is a horizontal sectional view taken on the line 2—2 of Figure 1 and illustrating in detail the arrangement and design of the mulling balls and the scrapers and deflectors;

Figure 3 is a horizontal sectional view taken on the line 3—3 of Figure 1 and showing in detail the means whereby the outwardly bulged side wall of the sand receiving receptacle is releasably clamped in place so that it may be turned or adjusted bodily in connection with positioning of the discharge door;

Figure 4 is a perspective of one of the plow-type deflectors for directing or deflecting the scraped sand back against the side wall of the receptacle;

Figure 5 is an enlarged detail sectional view taken on the line 5—5 of Figure 4 and illustrating the cross-sectional design of the deflectors;

Figure 6 is a detail sectional view illustrating the manner in which the plows are mounted or connected with respect to the rotary cross-head so that they are free to turn or swing inwards in the event that they encounter scrap or other foreign articles in the sand;

Figure 7 is a vertical transverse sectional view taken on the line 7—7 of Figure 1 and illustrating in detail the manner in which the sand receiving receptacle is supported on the frame structure so that there is sufficient room or space beneath the bottom section of the gear housing to permit lowering of such section in connection with the inspection or repair of the speed reducing gearing between the motor and the cross-head;

Figure 8 is a perspective view showing the apparatus without the discharge door and one of the side wall forming sections and illustrating in detail the manner in which the balls, scrapers and plows are accessible for inspection or replacement purposes upon removal of one of the side wall sections;

Figure 9 is a perspective view showing the apparatus without the discharge door and one of the side wall forming sections and illustrating in detail the manner in which the balls, scrapers and plows are accessible for inspection or replacement purposes upon removal of one of the side wall sections;

Figure 10 is a fragmentary perspective view of the ring at the top of the receptacle side wall.

The apparatus which is shown in the drawings constitutes the preferred embodiment of the invention and is adapted primarily for use in a foundry or like establishment. It serves or operates as hereinafter described, to mul or mix moulding sand and comprises as the main or essential parts thereof a frame structure 11, an open top receptacle 12, a pair of mulling balls 13, a pair of scrapers 14, a pair of plow type deflectors 15, and an electric motor 16.

The frame structure 11 serves as a supporting medium for the receptacle 12, the mulling balls 13, and the other parts of the apparatus and is adapted to rest on the floor of the foundry in which the apparatus is used. It is rectangular, as shown in Figure 2, and consists of a pair of laterally spaced, parallelly arranged, horizontally extending side beams 17, a pair of transverse horizontally extending end beams 18, and a bed plate 19. The side beams 17 are in the form of I-beams and are held in laterally spaced relation by the end beams 18. The latter are also in the form of I-beams and extend between and are suitably secured to the end of the side beams. The bed-plate 19 rests on and extends between the top flanges of the side beams 17 at one end of the frame structure 11 and serves as a pedestal or bed for the electric motor 16.

The receptacle 12 is positioned over and spaced above the other end of the frame structure 11 and is adapted to be charged with a batch of sand to be mulled or otherwise conditioned for moulding purposes. It is circular as far as its general contour is concerned and consists of a circular bottom 20, an outwardly bulged annular side wall 21, a ring 22 at the top of the side wall, and a tubular member 23 in the central portion of said side wall. The bottom 20 is in the form of a casting and embodies four outwardly extending integral lugs 24. These lugs are arranged in pairs at opposite sides of the receptacle and rest on and are supported by four

upstanding or vertically extending legs 25. The lower ends of the legs rest on and are welded or otherwise fixedly secured to the top flanges of the side beams 17 of the frame structure 11 and the upper ends of the legs underlie the outer ends of the lugs. Bolts 26 extend vertically through the outer ends of the lugs and serve rigidly to connect the lugs to the upper ends of the legs 25. The legs together with the side beam 17 of the frame structure and the lugs 24 of the bottom 20 serve to hold the receptacle in a rigid manner and also in an elevated position with respect to the frame structure. The side wall 21 is substantially semicircular in cross-section and extends outwardly and upwardly and then inwardly from the marginal portion of the circular bottom 20. It surrounds the mulling balls 13 and consists of an annular series of complementary sections 27 (preferably six in number). The latter are arranged in abutting relation and embody integral depending L-shaped bottom flanges 28, integral outwardly extending side flanges 29, and integral upwardly extending top flanges 30. The bottom flanges 28 rest on the outer margin of the bottom 20 and have a plurality of clamp plates 31 applied thereto. These plates overlie and extend radially with respect to the receptacle bottom 20 and are supported at their inner ends by blocks 32. The outer ends of the clamp plates rest on the horizontally extending portions of the L-shaped flanges 28 and carry bolts 33, which extend through holes in the subjacent portion of the receptacle bottom 20 and are adapted when tightened to force the outer ends of the clamp plates into clamped relation with the flanges 28 and thus clamp or lock the outwardly bulged side wall 21 in fixed relation with the receptacle bottom 20. By loosening the bolts 33 the side wall may be released and turned bodily for adjustment purposes if desired. The blocks 32 rest on the receptacle bottom 20 and are secured in place by means of threaded studs 34 which project into internally threaded sockets in said bottom 20. Compression springs 35 extend around the central portions of the shanks of the bolts 33 and operate to urge the clamp plates upwards away from the L-shaped flanges 28 for side wall releasing purposes when the nuts on the bolts are loosened. The flanges 29 at the sides of the side wall forming sections 27 abut against one another and form seals whereby the sand within the receptacle is precluded from being forced outwards between the sections 27 during operation of the apparatus. They are articulate as shown in Figures 7 and 8, and are secured together in abutting relation by means of bolts 36 which extend through aligned holes 37 in the side flanges. By removing the proper bolts and clamp plates one or more of the side wall forming sections 27 may be readily removed either for replacement purposes or to provide access to the mulling balls or the scrapers and plow type deflectors. The top flanges 30 extend between the upper ends of the side flanges 29 and define a circular inlet or opening for the sand receiving receptacle 12. The ring 22 operates to guide the sand to be mulled through this opening into the receptacle. The lower end of this ring fits within the top flanges 30 of the side wall forming sections 27 and is removably secured in place by means of bolts 38 which extend through aligned holes 39 in the top flanges and the lower end of the ring. The tubular member 23 of the receptacle extends upwards from

the bottom 20 and is of such length that the upper end thereof terminates at substantially the same elevation as the top flanges of the side wall forming sections 27. The lower end of the member projects through a centrally disposed opening 40 in the receptacle bottom 20 and embodies an outwardly extending annular flange 41 which rests on the opening defining portion of the bottom 20 and is secured in place by means of an annular series of bolts 42. Said bolts 42 extend downwardly through the flange and into internally threaded sockets in said opening-defining portion of the bottom 20. In addition to the bottom 20, the sectional side wall 21, the ring 22 and the tubular member 23, the receptacle comprises an annular false bottom 43. This false bottom rests on the bolts 33 and 42, as shown in Figures 1 and 2, and extends between the tubular member 23 and the upper edges of the L-shaped flanges 28. It is flat throughout the entire area thereof and supports the portion of the sand which, during a mulling operation, is moved inwards over the receptacle bottom by the scrapers, and deflectors.

The mulling balls 13 are of slightly less diameter than the cross-sectional diameter of the outwardly bulged side wall. They comprise metallic cores 44 and solid rubber coverings 45 and are mounted on and fixedly secured to the lower ends of a pair of substantially vertically extending shafts 46. These shafts, as shown in Figure 1, extend through the cores 44 of the balls and embody at their lower ends enlarged heads 47 which engage the bottom portions of the cores and prevent downward movement of the balls with respect to the shafts. The upper ends of the shafts 46 fit within sleeve-like members 48 and are journaled in upper roller bearings 49 and lower roller bearings 50. The sleeve-like members 48 fit within semi-cylindrical sockets 51 in a cross-head 52 in the top portion of the sand receiving receptacle 12 and are removably secured in place by means of U-bolts 53. The latter surround the outer portions of the sleeve-like members 48 and are carried by the cross-head, as shown in Figures 2 and 8. The roller bearings 49 and 50 permit the shafts 46 to rotate and hence the balls 13 are permitted to spin during travel around the outwardly bulged side wall 21 of the receptacle. The upper bearings 49 consist of outer races within the upper portions of the sleeve members 48, inner races around the upper ends of the shafts 46, and roller bearings between the two races, and are arranged and constructed so that the shafts are held against downward axial displacement with respect to the members 48 and the cross-head 52. The lower roller bearings 50 consist of outer races within the lower portions of the sleeve-like members 48, inner races around the shafts 46, and roller bearings between the inner and outer races and are shaped and constructed as shown in Figure 1 so that they prevent upward axial displacement of the shafts with respect to the sleeve-like members. By reason of the fact that the members 48 are secured rigidly to the cross-head the axes about which the balls 13 rotate are fixed with respect to the cross-head and hence the mulling balls do not swing outward during operation of the apparatus and remain at a fixed distance from the receptacle side wall 21. The shafts 46 are so carried or mounted with respect to the cross-head that the balls are spaced inwards a small distance from the recep-

tacle side wall and operate when a predetermined quantity of sand is introduced into the receptacle and the apparatus is set into motion, as hereinafter described, to squeeze the sand between them and the outwardly bulged side wall 21. Upon removal of one or more of the sections which form the side wall 21 of the receptacle the mulling balls may be inspected or by loosening or removing the U-bolts 53 removed bodily from the receptacle. The cross-head 52 is fixedly connected by bolts 54 to an enlarged head 55 at the upper end of a vertically extending shaft 56. This shaft extends through the tubular member 23 of the receptacle and is driven, as hereinafter described, by the electric motor 16 so as to cause the balls 13 to swing or travel in a circular course around the outwardly bulged side wall 22 of the receptacle for sand mulling or mixing purposes. The upper end of the shaft 56 is journaled in a pair of roller bearings 57 in the upper end of the member 23 and the lower end of the shaft projects downwards beneath or beyond the member 23 and is journaled in a roller bearing 58.

The scrapers 14 are positioned directly behind the mulling balls 13 and operate during drive of the cross-head 52, that is, during operation of the apparatus, to scrape the mulled sand from the inner periphery of the outwardly bulged side wall of the receptacle and direct it inwards towards the central portion of the receptacle. They are arcuate, as shown in Figure 7, and substantially conform in curvature to the side wall 21. The lower ends of the scrapers terminate adjacent to the outer margin of the false bottom 43 and the upper ends of the scrapers are connected by brackets 59 to the central portions of a pair of pipes 60. The upper ends of these pipes fit within semi-cylindrical sockets 61 in a pair of lugs 62 on the cross-head and are fixedly secured in place by means of U-bolts 63. The latter surround the upper ends of the pipes 60 and are carried by the lugs 62, which as shown in Figure 2, are formed integrally with and project outwardly from the cross-head. The brackets 59 are disposed directly beneath the lugs 62 and have semi-cylindrical sockets 64 in which the pipes 60 fit. U-bolts 65 extend around the central portions of the pipes and through the brackets 59 and serve to connect the brackets together with the scrapers to the pipes. Said bolts 65 are placed under such clamping pressure as far as the pipes are concerned that in the event that scrap or any other foreign articles in the sand should become wedged between the scrapers and the outwardly bulged side wall of the receptacle, the scrapers are permitted to swing inwards out of their normal or operative position and thus release the scrap or foreign articles. Upon inward swing of the scrapers as a result of the latter encountering scrap as aforesaid, it is contemplated that the apparatus be stopped and the scrapers reset, that is, shifted back to their normal position. Vertically extending bolts 66 extend through the outer portions of the brackets 59 and serve fixedly or rigidly to secure the upper ends of the scrapers to the brackets. The inner faces of the scrapers are beveled or canted in such manner that the mulled sand when encountered by the scrapers is deflected inwards. The U-bolts 65 between the brackets 59 and the pipes 60 constitute hinge or pivotal connections whereby in response to excessive pressure the scrapers are permitted to

swing inwards from their normal or operative position.

The plow-type deflectors 15 are in the form of metal castings and are positioned directly in front of the mulling balls 13. They extend from the tubular member 23 of the sand receiving receptacle to the outwardly bulged side wall 21 and operate during drive of the cross-head 52 to receive the sand which is deflected inwards by the scrapers and to deflect or direct such sand outwards against all portions of the inner periphery or face of the side wall into a position wherein it is properly disposed for squeezing or mulling by the balls. The upper portions of the inner parts of the deflectors have integral semi-cylindrical sockets 67 in which the lower ends of the pipes 60 fit. U-bolts 68 extend around the lower ends of the pipes 60 and serve to connect the deflectors to the pipes. These bolts are carried by the deflectors and are placed under such clamping pressure with respect to the pipes that the deflectors are permitted to swing inwards in the event that the outer parts thereof are subjected to excessive pressure as the result of scrap or other foreign articles becoming wedged between them and the outwardly bulged receptacle side wall 21. Said outer parts of the deflectors are warped or canted as shown in Figure 4, so that a portion of the sand is directed upwards towards the upper portion of the receptacle side wall 21. The deflectors are so designed and shaped that during drive of the cross-head they deflect the entire batch or charge of sand in the receptacle outwards against the side wall 21. By employing scrapers of this type the entire mass or batch of sand is subjected to the mulling action of both balls during each revolution of the cross-head and homogeneous mulling results. The U-bolts 68 constitute pivotal or hinge connections whereby the plow-type deflectors are permitted to swing inwards in response to excessive pressure resulting from scrap and foreign articles in the sand becoming wedged between the outer parts of the deflectors and the receptacle side wall. If access to the deflectors is desired or it becomes necessary to replace or repair the deflectors for any reason it is only necessary to remove one of the sections 27. The outer parts of the deflectors are shaped conformably to the inner face of the lower portion of the side wall and project rearwardly from the scrapers 14, as shown in Figure 2.

The shaft 56 together with the cross-head 52, the mulling balls 13, the scrapers 14, and the plow-type deflectors 15, is driven by the electric motor 16 through the medium of speed reducing gearing in a cast metal housing 69 under the bottom 20 of the sand receiving receptacle. This housing consists of a fixed upper section 70 and a removable lower section 71, and is positioned between the legs 25 for supporting the receptacle in an elevated position with respect to the frame structure 11. The upper section 70 consists of a continuous side wall which is formed integrally with and depends from the receptacle bottom 20 and has an out-turned bottom flange 72. The lower section comprises a bottom wall and a continuous side wall. The side wall of the bottom section is formed integrally with and extends upwardly from the bottom wall and has an out-turned marginal top flange 73 which abuts against the bottom flange 72 of the top section of the housing. Bolts 74 extend through the flanges 72 and 73 and serve removably to con-

nect the bottom section of the housing to the top section 70. The electric motor 16 is aligned with the housing 11 and embodies an armature shaft 15 which projects from the motor housing casing in the direction of the sand receiving receptacle 12. The speed reducing gearing consists of a bevel pinion 76, a bevel gear 77, a pinion 78, and a gear 79. The bevel pinion 76 is fixed to one end of a horizontally extending shaft 80 and meshes with and serves to drive the bevel gear 77. The shaft 80 is journaled in a roller bearing 81 between the top and bottom sections of the housing 70 and is connected at its outer end by a coupling 82 to the projecting end of the armature shaft 15. The bevel gear 77 is keyed or otherwise fixedly secured to a vertically extending shaft 83 which, as shown in Figure 1, is journaled in an upper roller bearing 84 and a lower roller bearing 85. The pinion 78 is disposed above the bevel gear 77 and is fixed to the upper end of the shaft 83. It meshes with the gear 79 and serves to drive the latter in response to operation of the electric motor 16. The gear 79 is keyed to the lower end of the shaft 56 and operates to drive the latter together with the cross-head and the muller balls scrapers and plow-type deflectors. The upper roller bearing 84 extends between the upper end of the shaft 83 and a socket 86 in the upper housing section 70. The lower roller bearing 85 extends between the lower end of the shaft 83 and a socket formation 87 in the bottom section 71 of the housing 69. The upper bearing 84 is so arranged that upon release of the parts thereof the shaft 83 together with the bevel gear 77 and the pinion 78 may be dropped with the bottom housing section 71 when it is desired to inspect the speed reducing gearing. When it is necessary or desirable to check or inspect the gearing it is only necessary to release the upper roller bearing 84, uncouple the coupling 82, and remove the bolts 72. At the conclusion of the operations the bottom section 71 of the housing 69 is free and may be dropped between the side beams 17 of the frame structure 11. When the section 71 is dropped the shaft 83 with the bevel gear 77 and the pinion 78 and the shaft 80 with the pinion 76 drop with the section.

In order that the sand in the receptacle 12 may be discharged at the conclusion of a mulling operation one of the side wall forming sections 27 is provided with a substantially rectangular discharge opening 88. This opening is normally closed by a door 89 which is pivoted by way of a hinge 90 so as to swing outwardly and upwardly into its open position. The hinge 90 is fixed to the door 89 by bolts 91 and is pivotally connected at its upper end to a rod 92. The latter extends horizontally and is carried by a pair of laterally spaced lugs 93 which, as shown in Figure 8, are formed integrally with the upper portion of the side wall forming section having the discharge opening 88. The door 89 is shifted into and out of its closed position by means of a piston and cylinder device 94. The latter is supported by a frame 95 and comprises a cylinder 96 and a piston 97 in the cylinder. The frame 95 is carried by the sand receiving receptacle 12 and comprises a pair of substantially horizontal lower bars 98, a substantially horizontally extending upper bar 99, and a pair of uprights 100 between the lower and upper bars 98 and 99. The cylinder 96 of the device 94 extends substantially vertically and is pivotally connected at its upper end to a bolt 101 on the

upper bar 93. The piston 97 is slidably mounted in the cylinder and is adapted in response to the action of fluid under pressure to move back and forth in the cylinder. A stem 102 is connected to the piston and extends downwardly through the lower end of the cylinder. The lower end of the stem 102 is pivotally connected to one end of a substantially horizontally extending link 103. The other end of the link is pivotally connected to a lug 104 on the central portion of the hinge 99. A link 105 is pivotally connected to and extends outwardly from the outer end of the link 103, that is, the end to which the stem 102 is pivotally connected and is pivotally connected at its outer end to the lower bars 98. When the piston 97 of the device 94 is shifted upwards the stem 102 together with the links 103 and 105 swing the door outwardly and upwardly into its open position, as shown in dotted lines in Figure 1. When the piston is shifted downwards the stem and links operate to swing the door into its closed position. The link 105 is so arranged that when the door is in its closed position it is substantially locked in place.

The mulling apparatus is preferably driven or operated so that the cross-head 52 rotates at approximately 90 R. P. M. When the receptacle 12 is charged by introducing a batch of sand into it through the ring 22 and the motor is started to effect drive of the cross-head, the mulling balls 13 move in a circular course around the outwardly bulged side wall 21 and effect mulling or squeezing of the sand between them and the side wall. During drive of the cross-head the scrapers 14 which are located behind the mulling balls scrape the mulled sand from the side wall of the receptacle and move or deflect it inwards into contact with the plow-type deflectors 15. The latter, as hereinbefore pointed out, direct the entire mass of sand outwards against the side wall into the path of the mulling balls so that it is subject to the action of the balls. When the cross-head is driven at the aforementioned speed the sand is effectively aerated by the action of the scrapers and deflectors and is maintained in suspension. At the conclusion of the mulling operation the door 89 is swung upwards and outwards into its open position by proper actuation or manipulation of the device 94. As soon as the door is swung into its open position the deflectors during travel around the receptacle side wall fling the sand outwards through the discharge opening 88 and thus automatically effect discharge of the sand. When it is desired to inspect or replace the balls, scrapers or deflectors, it is only necessary, as hereinbefore pointed out, to remove one of the side wall forming sections 21. By reason of the fact that the side wall 21 of the receptacle is releasably clamped in place by means of the plates 31 it may be adjusted rotatively in order to bring the door closed discharge opening 88 into any desired angular position with respect to the frame structure 11. If it is desired to inspect the speed reducing gearing in the housing 69 it is only necessary, as previously described, to drop the bottom section 71 and thus provide access to the various parts of the gearing.

The herein described mulling apparatus occupies but a comparatively small amount of space and has an extremely large capacity for its size. Due to the construction and arrangement of the various component parts the appa-

ratus is extremely rugged and well fitted or adapted for its intended purpose.

Whereas the apparatus has been described as being adapted for use in a foundry in connection with mulling, mixing or reconditioning moulding sand, it is to be understood that the apparatus may also be used to mull or condition materials other than sand and of a plastic or semi-plastic character. In addition it is to be understood that the invention is not to be restricted to the details set forth, since these may be modified within the scope of the appended claims, without departing from the spirit and scope of the invention.

15 Having thus described the invention, what we claim as new and desire to secure by Letters Patent is:

1. A mulling apparatus of the character described comprising in combination a receptacle adapted to contain the material to be mulled and embodying a circular bottom and an annular side wall extending upwardly from the margin of the bottom and composed of an annular series of abutting separately formed complementary sections having the side margins thereof removably secured together and having their bottom margins removably secured to the receptacle bottom, a mulling element in the receptacle adapted to travel in a circular course around the side wall and effect mulling of the material between it and said side wall during travel in such course and arranged so that it is accessible for repair or removal upon removal of one or more of the side wall forming sections with respect to the adjoining sections of the series, and means for propelling the mulling element in said circular course.
2. A mulling apparatus of the character described comprising in combination a receptacle adapted to contain the material to be mulled and embodying a substantially flat circular bottom and an annular outwardly bulged side wall extending upwardly from the margin of the bottom and composed of an annular series of abutting separately formed complementary sections having the side margins thereof removably secured together and their bottom margins removably secured to said bottom margin, a revolvable cross-head in the central portion of the receptacle, a rotary mulling element carried releasably by and disposed beneath the cross-head and adapted to travel in a circular course around the side wall and effect mulling of the material between it and said side wall during travel in such course, and arranged so that it is accessible for repair or removal upon removal of one or more of the side wall forming sections from the aforesaid series and without removal of the cross-head, and means for driving the cross-head.
3. A mulling apparatus of the character described comprising in combination a receptacle adapted to contain the material to be mulled and embodying a substantially flat circular bottom and an annular side wall extending upwardly from the margin of the bottom and composed of an annular series of abutting separately formed complementary sections having the side margins thereof removably secured together and embodying integral bottom flanges of L-shaped cross section releasably clamped to the margin of the bottom, a revolvable cross-head in the central portion of the receptacle, a rotary mulling element carried releasably by the cross-head and adapted to travel in a circular course

around the side wall and effect mulling of the material between it and said side wall during travel in such course, and arranged so that it is accessible for repair or removal upon removal of one or more of said complementary sections from the aforesaid series without removal of the cross-head, and means for driving said cross-head.

4. A mulling apparatus of the character described comprising in combination a receptacle adapted to contain the material to be mulled and embodying a circular bottom and an annular side wall extending upwardly from the margin of the bottom and composed of an annular series of abutting separately formed complementary sections having the side margins thereof secured removably together and having their bottom margins removably secured to said margin of the bottom, a revolvable cross-head in the central portion of the receptacle, a mulling element carried releasably by the cross-head and adapted to travel in a circular course around the side wall and effect mulling of the material between it and said side wall and arranged so that it is accessible for repair or removal upon removal of one or more of the side wall forming sections from said series without removal of the cross-head, a scraper and deflector also carried releasably by the cross-head and arranged so that they operate respectively to scrape the mulled material from the side wall and to deflect it back against said wall into the path of the element and also so that they are accessible for repair or replacement upon removal of one or more of said sections from said series without removal of the cross-head, and means for driving said cross-head.

5. A mulling apparatus of the character described comprising in combination a receptacle adapted to contain the material to be mulled and embodying a fixed circular bottom and an annular upwardly extending side wall having a door closed discharge opening therein and releasably clamped to the margin of the bottom so that it may be turned or rotated bodily to any angular extent in order to change the position of the door closed discharge opening, a mulling element in the receptacle adapted to travel in a circular course around the side wall and effect mulling of the material between it and said side wall, means for propelling the mulling element in said course, and a deflector connected for conjoint travel with the mulling element and arranged and adapted to deflect the material outwardly into the path of the mulling element during a mulling operation and also to discharge the mulled material from the receptacle via the opening when the door for the latter is open.

6. A mulling apparatus of the character described comprising in combination an open top receptacle adapted to contain the material to be mulled and embodying a substantially flat circular bottom and an annular upwardly extending side wall having a door closed discharge opening therein and also having a bottom flange resting on the margin of said bottom, releasable clamping members applied to said flange and adapted to secure the side wall in place and upon release thereof to permit the side wall to be turned or adjusted bodily in order to position said door closed discharge opening as desired, a circular false bottom positioned over the first mentioned bottom and extending inwardly from the top of the bottom flange and over the clamping members, a mulling element in the recep-

tacle adapted to travel in a circular course over the false bottom and around the side wall and effect mulling of the material between it and said side wall, means for propelling the mulling element in said course, and a deflector connected for conjoint travel with the mulling element and arranged and adapted to deflect the material outwardly into the path of the mulling element during a mulling operation and also to discharge the mulled material from the receptacle via the opening when the door for the latter is open.

7. A mulling apparatus of the character described comprising in combination an open top receptacle adapted to contain the material to be mulled and embodying a substantially flat circular bottom and an annular upwardly extending side wall having a door closed discharge opening therein and also having an inturned annular flange of L-shaped cross section resting on the margin of the bottom, radially extending clamping members around and over the margin of the bottom having the outer ends thereof resting on the bottom portion of the flange and having bolt connections between them and the bottom for urging them downwards and into clamped relation with said flange, and adapted upon release of said bolt connections to release the side wall and permit it to be turned or rotated bodily to any angular extent in order to position the door closed discharge opening as desired, a mulling element in the receptacle adapted to travel in a circular course around the side wall and effect mulling of the material between it and said side wall, means for propelling the mulling element in said course, and a deflector connected for conjoint travel with the mulling element and arranged and adapted to deflect the material outwardly into the path of the mulling element during a mulling operation and also to discharge the mulled material from the receptacle via the opening when the door for the latter is open.

8. A mulling apparatus of the character described comprising in combination an open top receptacle adapted to contain the material to be mulled and embodying a substantially flat circular bottom and an annular upwardly extending side wall having a door closed discharge opening therein and also having an inturned annular flange resting on the margin of the bottom, releasable flange engaging clamping members carried by the bottom and adapted upon release thereof to permit the side wall to be turned or adjusted bodily in order to position the door opening as desired, a circular false bottom overlying the receptacle bottom and serving to cover the clamping members, a mulling element in the receptacle adapted to travel in a circular course over the false bottom and around the side wall and to effect mulling of the material between it and said side wall during travel in such course, and means for propelling the mulling element in said circular course.

9. A mulling apparatus of the character described comprising in combination a receptacle adapted to contain the material to be mulled and embodying a circular bottom and an annular upwardly extending side wall having a door closed discharge opening therein and composed of an annular series of complementary sections secured removably together and having flanges resting on the margin of the bottom, releasable clamping means applied to said flanges and adapted upon release thereof to permit the sections to be removed and also to permit the side wall to be

turned or adjusted bodily in order to position the discharge opening as desired, a mulling element in the receptacle adapted to travel in a circular course around the side wall and effect mulling of the material between it and said side wall during travel in such course and arranged so that it is accessible for repair or removal upon removal of one or more of the side wall forming sections, and means for propelling the mulling element in said circular course.

10. A mulling apparatus of the character described comprising in combination a receptacle adapted to contain the material to be mulled and embodying a substantially flat circular bottom and an annular upwardly extending outwardly bulged side wall of substantially semi-circular cross-section having a door closed discharge opening therein and composed of an annular series of complemental sections secured removably together and having bottom flanges resting on the margin of the bottom, releasable flange engaging clamping members carried by the margin of the bottom and adapted upon release thereof to permit the sections to be removed and also to permit the side wall to be turned or adjusted bodily in order to position the discharge opening as desired, and a freely rotatable mulling ball in the receptacle adapted to travel in a circular course around the side wall and effect mulling of the material between it and said side wall during travel in such course and arranged so that it is accessible for repair or removal upon removal of one or more of the side wall forming sections, and means for propelling the mulling ball in said circular course.

11. A mulling apparatus of the character described comprising in combination a receptacle adapted to contain the material to be mulled and embodying a substantially flat circular bottom and an annular upwardly extending outwardly bulged side wall having a door closed opening therein and composed of an annular series of complemental sections secured removably together and having inturned bottom flanges resting on the margin of the bottom, releasable flange engaging clamping members carried by the margin of the bottom and adapted upon release thereof to permit the sections to be removed and also to permit the side wall to be turned or adjusted bodily in order to position the door opening as desired, a substantially flat circular false bottom overlying the receptacle bottom and serving to cover the members, a rotatable mulling element adapted to travel in a circular course over the false bottom and around the side wall and effect mulling of the material between it and said side wall during travel in such course, and arranged so that it is accessible for repair or removal upon removal of one or more of the side wall forming sections, and means for propelling the element in said circular course.

12. A mulling apparatus of the character described comprising in combination a receptacle adapted to contain the material to be mulled and embodying a substantially flat circular bottom and an annular upwardly extending outwardly bulged side wall having a door closed opening therein and composed of an annular series of complemental sections secured removably together and having inturned bottom flanges resting on the margin of the bottom, releasable flange engaging clamping members carried by the margin of the bottom and adapted upon release thereof to permit the sec-

tions to be removed and also to permit the side wall to be turned or adjusted bodily in order to position the door opening as desired, a substantially flat circular false bottom overlying the receptacle bottom and serving to cover the members, a revolvable cross-head in the central portion of the receptacle, a mulling ball carried by the cross-head and adapted to travel in a circular course over the false bottom and around the side wall and effect mulling of the material between it and said side wall during travel in such course, and arranged so that it is accessible for repair or removal upon removal of one or more of the side wall forming sections, a scraper and deflector also carried by the cross-head and arranged so that they operate respectively to scrape the mulled material from the side wall and to deflect it back against said wall into the path of the element, and also so that they are accessible for repair or replacement purposes upon removal of one or more of said sections, and means for driving the cross-head.

13. A mulling apparatus of the character described comprising in combination a receptacle adapted to contain the material to be mulled and embodying a circular bottom and an annular side wall extending upwardly from the margin of the bottom, a revolvable cross-head in the central portion of the receptacle, a substantially vertical shaft carried by the cross-head and held against lateral displacement or swinging movement, a rotary mulling element on the shaft held by the latter at a fixed distance away from the side wall of the receptacle and adapted during drive of the cross-head to move in a circular course around said side wall and to effect mulling of the material between it and the side wall, and means for driving the cross-head.

14. A mulling apparatus of the character described comprising in combination a receptacle adapted to contain the material to be mulled and embodying a circular bottom and an annular side wall extending upwardly from the margin of the bottom, a revolvable cross-head in the upper central portion of the receptacle, a substantially vertical shaft depending from the cross-head and connected to the latter so that it is rotatable without lateral displacement, a rotatable mulling element on the lower end of the shaft held by said shaft at a predetermined distance inwardly of the side wall and adapted during drive of the cross-head to travel in a circular course around said side wall and to effect mulling of the material between it and said side wall, and means for driving the cross-head.

15. A mulling apparatus of the character described comprising in combination a receptacle adapted to contain the material to be mulled and embodying a circular bottom and an annular side wall extending upwardly from the margin of the bottom and composed of an annular series of complemental sections removably secured together, a revolvable cross-head disposed in the upper central portion of the receptacle and having a substantially semi-circular socket therein, a sleeve member releasably secured in the socket, a substantially vertical shaft having the upper end thereof journaled in roller bearings in the sleeve member for rotation on its axis without lateral displacement, a rotary mulling element on the lower end of the shaft adapted upon drive of the cross-head to

travel in a circular course around the side wall and effect mulling of the material between it and said side wall and also adapted upon release of the sleeve member and removal of one or more of the side wall forming sections to be removed by lateral shift thereof through the space normally closed by said one or more sections, and means for driving the cross-head.

16. A mulling apparatus of the character described comprising in combination a receptacle adapted to contain the material to be mulled and embodying a circular bottom and an annular upwardly extending side wall, a revolvable cross-head in the central portion of the receptacle, a mulling element adapted during drive of said cross-head to be driven in a circular course around the side wall and to effect mulling of the material between it and said side wall, a scraper for scraping the mulled material from the side wall adapted to rotate with the cross-head and connected by clamp means to said cross-head so that in response to excessive pressure resulting from wedging of foreign material or scrap between it and the side wall it is adapted to swing inwards about a substantially vertical axis, and means for driving the cross-head.

17. A mulling apparatus of the character described comprising in combination a receptacle adapted to contain the material to be mulled and embodying a circular bottom and an outwardly bulged side wall extending upwardly from the margin of the bottom, a revolvable cross-head in the central portion of the receptacle, a mulling ball carried by the cross-head in spaced relation with the side wall and adapted during drive of said cross-head to travel in a circular course around the side wall and effect mulling of the material between it and said side wall, an arcuate scraper for scraping the mulled material from the side wall carried by the cross-head in spaced relation with the side wall and for conjoint travel with the ball and mounted by way of pivot type clamping means so that it is adapted to swing inwards in response to excessive pressure thereagainst resulting from foreign material or scrap wedging between it and said side wall, and means for driving the cross head.

18. A mulling apparatus of the character described comprising in combination a receptacle adapted to contain the material to be mulled and embodying a circular bottom and a continuous side wall extending upwardly from the margin of the bottom, a revolvable cross-head disposed in the central portion of the receptacle and having a vertical pipe, a rotary mulling element carried by the cross-head in front of the pipe and adjacent the receptacle side wall and adapted during drive of the cross-head to travel in a circular course around the side wall and effect mulling of the material between it and said side wall, a scraper adapted to scrape the mulled material from the side wall and deflect it inwards and connected to said pipe by clamping means so that it is adapted to swing inwards about the axis of the pipe out of its normal operative position in response to excessive pressure thereagainst resulting from foreign material or scrap wedging itself between the scraper and the side wall, and means for driving the cross-head.

19. A mulling apparatus of the character described comprising in combination a receptacle adapted to contain the material to be mulled and embodying a circular bottom and an annular upwardly extending side wall, a revolvable cross-head in the central portion of the receptacle, a

5 mulling element adapted during drive of said cross-head to travel in a circular course around the side wall and effect mulling of the material between it and said side wall, a deflector in front of the mulling element for deflecting the material outwards from the central portion of the receptacle against the side wall and into the path of said element adapted to rotate with the cross-head and connected to the cross-head by clamping means so that in response to excessive pressure resulting from foreign material or scrap wedging between it and the side wall it is adapted to swing inwards about a substantially vertical axis out of its normal operative position, and means for driving the cross-head.

20. A mulling apparatus of the character described comprising in combination a receptacle adapted to contain the material to be mulled and embodying a circular bottom and an outwardly bulged side wall extending upwardly from the margin of the bottom, a revolvable cross-head in the central portion of the receptacle, a rotary mulling ball carried by the cross-head in spaced relation with the side wall and adapted during drive of said cross-head to travel in a circular course around the side wall and effect mulling of the material between it and said side wall, a plow-type deflector for deflecting the material in the central portion of the receptacle outwards and upwards against all portions of the side wall into the path of the mulling ball, carried by the cross-head in front of the ball and for conjoint travel with the latter and connected to the cross-head by pivot type clamping means, so that it is adapted to swing inwards in response to excessive pressure resulting from foreign material or scrap wedging between it and said side wall, and means for driving the cross-head.

21. A mulling apparatus of the character described comprising in combination a receptacle adapted to contain the material to be mulled and embodying a substantially flat circular bottom and an annular side wall extending upwardly from the margin of the bottom, a revolvable cross-head disposed in the central portion of the receptacle and having a vertical pipe, a rotary mulling element carried by the cross-head behind the pipe and adjacent the side wall and adapted during drive of the cross-head to travel in a circular course around the side wall and effect mulling of the material between it and said side wall, a plow type deflector adapted to deflect the material in the central portion of the receptacle outwardly against all portions of the side wall and into the path of the mulling element and mounted on the pipe so that it is adapted to swing inwards about the axis of the pipe and out of its normal operative position in response to excessive pressure thereagainst resulting from foreign material or scrap wedging itself between the deflector and the side wall, and means for driving the cross-head.

22. A mulling apparatus of the character described comprising in combination a receptacle adapted to contain the material to be mulled and embodying a substantially flat circular bottom and an annular side wall extending upwardly from the margin of the bottom, a revolvable cross-head disposed in the central portion of the receptacle and having a vertical pipe, a rotary mulling element carried by the cross-head and adapted during drive of the latter to travel in a circular course around the side wall and effect mulling of the material between it and said side wall, a scraper and a deflector operative respec-

tively to scrape and deflect inwardly the mulled material from the receptacle side wall and to deflect outwards the scraped material against the side wall into the path of the mulling element and connected by clamping means to the pipe for conjoint travel with the mulling element and so that they are both adapted to swing inwards about the axis of the pipe in response to excessive pressure resulting from the wedging of foreign material or scrap between them and the side wall, and means for driving the cross-head.

23. A mulling apparatus of the character described comprising in combination a receptacle adapted to contain the material to be mulled and embodying a circular bottom and an annular outwardly bulged side wall extending upwardly from the margin of the bottom, a revolvable cross-head in the central portion of the receptacle, a substantially vertical shaft carried by the

cross-head and held against lateral displacement, a rotary mulling ball on the shaft held by the latter a fixed distance away from the side wall of the receptacle and adapted during drive 5 of the cross-head to move in a circular course around said side wall and to effect mulling of the material between it and the side wall, means carried by the cross-head for rotation therewith for controlling the material so that during each time the ball travels around the side wall the entire mass of material is flung outwards in a scattered and aerated manner against substantially all portions of the inner face of said side wall into the path of the ball and is then after 10 mulling by the ball scraped and deflected inwards, and means for driving the cross-head.
